SUPPORT FOR CONTAINERS OF PASTELIKE
SUBSTANCES HAVING FLUID PRESSURE
MEANS FOR DISPENSING SAID SUB-
STANCES

John L. Taylor, La Habra Heights, Calif.

Application July 8, 1946, Serial No. 681,944

1 Claim. (Cl. 222—389)

1

This invention relates to dispensing apparatus, and especially to apparatus for dispensing detergent material, such as paste soap.

It is known to provide apparatus for dispensing soap, or similar material, for washing the hands. Such apparatus is commonly arranged for operation by force exerted by the hand to deliver a small quantity of the material. Due to the fact that the force conveniently available in this manner is comparatively small, the material capable of use in such apparatus is limited to such as have free flowing characteristics as, for example, material in powder, or liquid form. Under many conditions, such material is quite satisfactory.

In many instances, such free flowing material dries out before it is used up entirely. The resulting caked material is difficult to handle even when known mechanical devices are used to express the material from the container.

A material having satisfactory cleansing properties is preferably in the form of a heavy paste, possibly carrying some abrasive material. Such material, especially, cannot be handled readily by apparatus relying on manual pressure to deliver the material, and it has been the usual custom to supply such material in open cans or containers, from which it is scooped by the user's hands, as required.

This is a wasteful practice, as material substantially in excess of the quantity actually required will usually be taken. Furthermore, the material in the container is soiled or contaminated by contact with the user's hands.

It is an object of this invention to provide a dispenser for detergent material, or the like, utilizing power, such as fluid pressure for the dispensing operation.

It is another object of this invention to provide apparatus for dispensing detergent material under pressure, and which is operable in a conventional manner by the user.

It is another object of this invention to provide dispensing apparatus for detergent material in paste, or semi-liquid form, which is readily operable in a conventional manner.

It is still another object of this invention to provide a dispenser for paste, or semi-liquid detergent material, having novel means for renewing the supply of such material.

This invention possesses many other advantages, and has other objects which may be made more clearly apparent from a consideration of several embodiments of the invention. For this purpose there are shown a few forms

2

in the drawings accompanying and forming part of the present specification. The forms will now be described in detail illustrating the general principles of the invention; but it is to be understood that this detailed description is not to be taken in a limiting sense, since the scope of this invention is best defined by the appended claim.

In the drawings:

Figure 1 is a sectional view, partly in elevation, 10 of a dispenser incorporating the features of the invention;

Fig. 2 is a cross section, taken as indicated by line 2—2 of Fig. 1;

Fig. 3 is a fragmentary, transverse section of 15 a container adapted for use with the dispenser of Fig. 1;

Fig. 4 is a detail section, taken as indicated by line 4—4 of Fig. 1;

Fig. 5 is an elevation, partly in section, of a 20 modified form of dispenser; and

Fig. 6 is a plan view, partly in section, of the dispenser of Fig. 5.

In the form of the invention shown in Figs. 1 to 4, the dispenser is shown as comprising a 25 cylindrical shell 5, closed at its upper and lower ends, and appropriately supported, as by a wall bracket 6. The shell 5 has a fluid-tight piston 7 therein, forming a movable wall and dividing the interior of the shell 5 into an expansible chamber 5-a, and a space 5-b containing the material to be dispensed, such material being a detergent material, or the like, such as a heavy paste. Pressure is exerted on the material in the space 5-b by supplying fluid pressure to the chamber 5-a, 30 so that it will be discharged through a conduit 8 provided with one or more valves 9, when the valve or valves are opened.

Referring in detail to the structure, it is contemplated that the detergent material, or soap paste, be supplied to the user in portable containers 10, one of which is illustrated in Fig. 3. This container is formed of light sheet material, such as tin plate, and comprises a cylindrical body 11, closed in a conventional manner by a 45 removable cover 12, and having its bottom 13 arranged so that a suitable discharge opening may be formed readily therein. For this purpose, an opening 14 may be provided in the bottom, and covered by a patch 15 secured exteriorly 50 on the bottom 13, as by soft solder, so as to be easily removed when desired.

The bracket 6 is arranged to mount the container 10 so that the body 11 thereof forms the shell 5. The bracket 6 comprises an arm 16 arranged to project horizontally from a wall or

other supporting surface S , to which it is secured, as by screws 17 , engaging a vertical extension 18 of the arm 16 .

A pair of shouldered spacer rods 19 and 20 , extending upwardly from arm 16 , support a head or closure member 21 for sealing and closing the upper end of the body 11 , in lieu of the cover 12 which is removed when the container 10 is mounted for use. For this purpose, the head 21 is provided with an annular flange 22 adapted to enter the upper end of the body 11 , and having an exterior groove $22-a$ for accommodating a resilient packing ring 23 of rubber, or other suitable material.

The container body 11 has an outwardly flaring lip $11-a$ for engaging the packing ring 23 . Means are provided for urging the body 11 upwardly to cause the lip $11-a$ to compress the packing ring 23 against the head 21 . This means is shown as comprising an upstanding, exteriorly threaded tubular member 24 carried by the bracket arm 16 . Thus, the arm 16 may have a threaded opening 25 (Fig. 4), for receiving the member 24 , which has a head 26 engaging the bottom of the arm 16 .

A nut 27 , having a cylindrical extension $27-a$, is threaded on the member 24 , the extension $27-a$ being adapted to engage a circular recess 28 in the bottom of a lower head 29 . This lower head 29 is in the form of a circular plate and is of suitable size to fit readily within the flanged portion $13-a$ of the container bottom 13 .

The arrangement is such that, when the nut 27 is rotated to move upwardly on the member 24 , the container 10 is moved upwardly to seal against the head 21 . When the nut 27 is rotated to move downwardly, the container 10 moves downwardly below the flange 22 , and then may be removed readily by lifting sufficiently to cause flange $13-a$ to clear the lower head 29 , and moving the container laterally from between the rods or posts 19 and 20 .

The piston 7 comprises a flat disc 30 with a peripheral flange 31 of a suitable exterior diameter to slide freely within the shell 5 . Suitable packing 32 is provided to prevent fluid leakage past the piston. A central hub 33 having an upwardly directed tapped hole 34 is provided for a purpose to be later pointed out. The piston 7 and the head 21 cooperate to form the expandable chamber $5-a$ to which fluid is admitted by the conduit 35 , connected with an opening 36 in the head.

Since the dispenser will, in general, be used in wash rooms, or the like, where water under pressure is available, the conduit 35 will usually be connected to such water supply. However, compressed air may be used if desired. In either case, a valve (not shown) will be provided in the conduit 35 to shut off the fluid pressure when desired; as, for example, to install a filled container 10 .

It will be obvious that fluid pressure in chamber $5-a$ will urge the piston 7 downwardly on the material in the space $5-b$, this material being, as previously indicated, capable of flow under the applied pressure.

Since the member 24 and nut 27 are to provide the discharge passage for this material, an opening 37 is provided extending through the lower head 29 from the recess 28 . The opening 14 in the container bottom 13 is arranged to register with port 37 when the container 10 is installed on the bracket 6 , the patch 15 being removed before installation. A gasket 38 , ac-

commodated in a groove 39 extending about the opening 37 , serves to prevent leakage of the material between the lower head 29 and the bottom 13 , the bottom 13 being urged downwardly against the gasket 38 by the pressure of the material in the container. Additionally, a gasket 40 is confined between the upper end of nut 27 and the bottom of recess 28 .

The head 26 of the member 24 has an internal thread $26-a$ for accommodating an elbow 41 to which the conduit 8 is connected. This conduit 8 may have any desired number of discharge valves 9 thereon, two being shown by way of example, or a single valve may be secured directly to the head 26 .

As clearly shown in Fig. 1, each valve 9 comprises a tubular member 43 which the fluent material enters freely. The member 43 has an upwardly facing valve seat 44 , and a reduced tubular extension 45 forming the outlet. A valve member 46 cooperates with the valve seat 44 to close the outlet 45 , being urged to seat by the pressure of the fluent material. The valve member 46 has an operating stem 47 projecting outwardly through the outlet 45 .

When it is desired to obtain material from the dispenser, the user places his hand beneath the valve 9 and pushes upwardly on stem 47 , unseating the valve 46 and causing material to flow through the outlet 45 . Upon release of the stem, the valve 46 reseats and delivery of material ceases. Since the area of the valve is small, moderate force suffices to open the valve, the pressure of the material immediately closing the valve. The material is delivered slowly, since the effective opening of the valve is small. This slow delivery, and the fact that the pressure of the material urges the valve to seat at all times, ensures against waste.

When the entire contents of a container have been used, the fluid pressure in chamber $5-a$ is shut off, and the nut 27 is slackened off sufficiently to allow the container 10 to be removed. A bar or rod is then screwed into the piston boss 33 , and the piston 7 is removed. The cover 12 and the patch 15 of a filled container 10 are then removed, the piston 7 inserted on top of the material therein, and the container placed on the lower head 29 . The nut 27 is then operated to urge the container lip $11-a$ to seal against the head gasket 23 . The fluid pressure is then turned on, and the dispenser is again ready for use.

An ornamental casing 49 is provided for enclosing the dispenser, being arranged to telescope over the head 21 and extending to the bottom of the bracket arm 16 . A cut-out $49-a$ is provided at the back of the casing for accommodating the arm 16 . The casing 49 slides freely over the head 21 , so that it may be removed and replaced readily when a new container 10 is to be installed.

In the modified form of dispenser shown in Figs. 5 and 6, a cylindrical shell 50 , having a packed piston 51 slidable therein, is provided as before. The upper and lower ends of the shell 50 are closed, respectively, by heads 52 and 53 secured by through bolts 54 and rendered fluid-tight by gaskets 56 and 57 . The dispenser is mounted on the horizontal arm of a bracket 58 , and secured thereto, as by a pair of the bolts 54 arranged to extend through the bracket arm.

Fluid pressure is admitted to the shell above the piston 51 by a valve controlled conduit 59 connected with a suitable source (not shown). A valve controlled outlet 60 is also provided. A discharge outlet 61 for the soap paste, or

other material, is provided, and is shown as equipped with a single valve 9, although additional outlet valves may be provided, as in the first described form of the invention.

The soap paste is discharged under the pressure exerted by the piston 51, as before, but the shell 50 is filled initially, as well as subsequently, through a one-way pressure fitting 62, such as a conventional Alemite, or Zerk fitting.

When the shell 50 requires filling, the valve in the pressure conduit 59 is closed and the outlet valve 60 is opened. A grease gun adapted for use with the fitting 62 is then filled with the soap paste, or other material, which is forced into the shell through the fitting 62. This forces the piston 51 to rise, the fluid above it escaping through the outlet 60. Upon the shell 50 being filled as required, the outlet 60 is closed, and fluid pressure admitted through conduit 59. This causes the piston 51 to exert pressure on the material in the shell 50. The fitting 62 automatically closes to prevent escape of any of this material, which can be discharged only by operation of the valve 9.

The inventor claims:

In a device of the character described: a lower head; an upper head; a container having an open top and a bottom with an aperture therein, said bottom resting on said lower head, the upper head serving to close said open top of said container; a piston in the container; means for admitting fluid

under pressure through the upper head; there being an aperture in the lower head registering with said aperture in the bottom of the container; an outlet means connected to the aperture in the lower head; means for urging the two heads toward each other; inlet means connected to the interior of the container and carried by the lower head; said inlet means including a valve fitting threaded into the lower head, and means for relieving the pressure above the piston.
